F. H. NULLMEYER

REEL

Filed Aug. 9, 1923

INVENTOR
Frank H. Nullmeyer
By Cyrus Feltus Parmelee
inventor

UNITED STATES PATENT OFFICE.

FRANK H. NULLMEYER, OF STRUTHERS, OHIO.

REEL.

Application filed August 9, 1923. Serial No. 656,575.

To all whom it may concern:

Be it known that I, FRANK H. NULLMEYER, a citizen of the United States, residing at Struthers, county of Mahoning, and State of Ohio, have invented a new and useful Improvement in Reels, of which the following is a full, clear, and exact description.

This invention relates to an improvement in reels, and more particularly to reels for holding wire for fencing, etc.

One of the objects of my invention is to provide a built-up reel formed of a plurality of members, all of which are adapted to be stacked face to face.

Another object of my invention is to provide a reel all of whose parts can be made of wire rods and in which all the parts can be readily and quickly assembled without the use of tools, as well as a reel which is rigid when assembled and which will not collapse when wire or other material is wound thereon.

A further object of my invention is to provide a reel having a spindle bearing member at each end, for the reception of a suitable member about which the reel can be rotated when wire is drawn therefrom.

The precise nature of my invention will be best understood by reference to the accompanying drawings, which will now be described, it being premised, however, that various changes may be made without departing from the spirit or scope of my invention as defined in the appended claims.

Figure 1 is a perspective view of one form of reel made in accordance with my invention; and

Figure 2 is a similar view of another form of reel.

The reel shown in Figure 1 of the drawings comprises two end or head members each having three radially disposed arms 2, which form the heads of the reel. The body of the reel is formed of three rods each having a longitudinally extending portion 3 and laterally extending portions 4, the ends of which are provided with hooks 5. The body members extend from head to head between the arms 2 of the end members, while the laterally extending portions 4 of the various body members extend in a radial direction, the hooks 5 thereof engaging triangular ring members 6 which form bearing members for a suitable member about which the reel may be rotated when unwinding the wire or other material from the reel.

In assembling the reel, the three body members are hooked to the ring members 6, and the end forming members are positioned between two of the body members, and are then rocked to position, one of the arms of each end member being between two body members, and the end members are then pushed towards the ends of the structure. Each body member is also provided with a sloping portion 7 at the end of the longitudinal portion 3, which will assist in retaining the end members in an upright position.

The arms 2 of the end members, as well as the rings 6 and the length of the arms 4 are so proportioned that when the various parts are assembled, the tension of the various parts will hold them in such a manner as to form a substantially rigid structure.

In the structure shown in Figure 1, the hooks 5 are left open so that the reel parts can readily be assembled or knocked down.

In Figure 2 I have shown a structure similar to that shown in Figure 1, and in which I have used the same reference characters for designating similar parts.

In this form, the end members are provided with four arms 2', while the body is formed of four members instead of three as in Figure 1.

In this structure, the hooked ends 5 of the body members have been closed to a certain extent, so that the rings 6' and body forming members cannot be separated without exerting some force.

In either form of reel, the various elements can be bundled in flat formation, or if desired the heads can be bundled in flat formation, while the body members for each reel can be hooked about a ring member and maintained in the same plane along one of the sides of the rings 6 or 6', and can be readily bundled in this manner.

The advantages of my invention result from the provision of a reel formed of similar head and body forming members, which are connected to each other in such a manner that the reel parts can readily be assembled without the use of tools, and which are so arranged that when the parts are assembled, the various members will be under tension to retain the parts in position, and in which the head members are restrained from lateral movement by the body forming members.

A further advantage results from the provision of a reel of this character in which all

portions of each reel forming element extend or lie in the same plane.

It will be noted from the drawings that the head or end members which are subjected to lateral pressure or bending stresses by the wire when wound on the reel, are made of heavier gage wire than the body members, which are merely subjected to tension stresses.

10 I claim:

1. A reel comprising head members each providing arms, body forming members extending from head to head between the arms of the heads, and a central ring member at 15 each end of the reel connected to the ends of the body members, substantially as described.

2. A reel comprising head members, each providing arms, a plurality of body members 20 extending from head to head between adjacent arms, there being an equal number of body members and arms on each head, a

ring-like member at each end of the reel, and hooks at the ends of the body members in engagement with the rings, substantially as described. 25

3. A reel comprising heads, each formed of two endless wires and each having three arms, three body members having longitudinal portions extending from head to head between the arms of the heads, each body member having radial portions with hooked ends, and a ring at each end of the reel engaged by the hooks on the body members, substantially as described. 30

4. A reel comprising head members, two ring members, and a plurality of body forming members connected to the ring members and engaging the head members, the various elements of each reel forming member lying 35 in one plane, substantially as described. 40

In testimony whereof I have hereunto set my hand.

FRANK H. NULLMEYER.
